UNITED STATES PATENT OFFICE

ARTHUR L. MERRIN, OF BELLINGHAM, WASHINGTON.

ILLUMINATED SIGN.

968,177.

Specification of Letters Patent. Patented Aug. 23, 1910.

Application filed November 29, 1909. Serial No. 583,432.

To all whom it may concern:

Be it known that I, ARTHUR L. MERRIN, a citizen of the United States, and a resident of Bellingham, in the county of Whatcom and State of Washington, have invented certain new and useful Improvements in Illuminated Signs, of which the following is a specification.

My invention relates to an improvement in illuminated signs which may also be read during the night without artificial illumination, especially to those having the so-called trough letters or characters which have deep or flanged sides; and consists in a suitable structure and attachments for placing the source of light within a box the sides whereof bear the trough letters, the back or plane part of said letters being transparent permitting the interior light to pass therethrough; and the object of my invention is to economize in the amount of artificial light required as compared to the trough letter signs in which the sources of light are external and within said trough letters, and to accomplish a more even illumination than is possible by the spot lighting of the usual form referred to.

My invention is illustrated in the single sheet of drawings accompanying this application and forming a part thereof in which similar characters refer to similar parts in the several views and in which—

Figure 1 is a side view of my improved sign in longitudinal sectional elevation on the line *a b* of Fig. 2; Fig. 2 is an end view in transverse sectional elevation on the line *c d* of Fig. 3; Fig. 3 is an exterior side elevation of the side, the interior of which is shown in Fig. 1, and Fig. 4 is an end elevation in section on the line *e f* of Fig. 3 in which some enlargement is used especially as regards the thickness of the metal parts in order that these parts may be shown in cross section.

More specifically: 1 and 2 are the sides and 1^a and 2^a are the ends of the box, preferably of sheet metal; 3 and 4 are respectively the top and bottom of said box, preferably of wood; 5 and 6 are two doors hinged to the said bottom 4, being suited to close openings in said bottom suited for the admission of one's hand into the interior. Door 6 is illustrated as standing open and door 5 as being closed while the dotted outline at 5' is door 5 in its open position.

5^a and 6^a are buttons attached to bottom 4 for retaining doors 5 and 6 in closed position.

7 and 8 are two insulated electric conductors leading from electric lamps 9, 9, 9, located within said box and attached to the floor 4 thereof. 10, 10 are reflecting surfaces or mirrors retained within said box immediately beneath the top 3. 11, 11, etc., are clamping screws suited to retain said mirrors in place.

12 is a cleat attached to the lower side of top 3, extending longitudinally through the middle thereof; against it rests the upper edges of the mirrors 10, 10.

13, 14 and 15 are three standards rigidly attached to the bottom 4 and standing within said box preferably in a medial longitudinal line. Furthermore, standard 13 is located transversely between the middle letters of the sign; standard 14 is located opposite the letter B of the side illustrated in Figs. 1 and 3, and standard 15 is located opposite letter B on the opposite, or side 1, of the box.

16, 17 and 18 are the exterior flanges of three trough letters B, O and N, respectively, constituting the sign illustrated.

17^a, Fig. 2 is the exterior flange of letter O on said opposite side 1.

16^a, 16^b are the flange borders of the interior outlines of letter B.

17^b is the flanger borders of the interior outline of letter O. 16^c, 17^c and 18^c are panes of glass secured within said box against side 2 behind the letters B, O and N on said side. Three similar panes are attached to side 1, only one of which 17^c being shown in Fig. 2. These panes of glass form transparent backing for the letters B, O, and N, on each of said sides 1 and 2.

19, Fig. 2, is a rod the outer end of which passes through a hole in pane 17^c and is rigidly attached to a disk of metal 19^b which is in turn rigidly attached to the metal bottom of the interior portion 17^a of the letter O on the side 1 of said box. The other end of this rod 19 is threaded and passes through a hole in standard 13. On said threaded body, on each side of standard 13 are clamping nuts 19^a, 19^b by which the distance between standard 13 and side 1 is first adjusted and then said rod is securely fastened to said standard by said nuts. By this means, the interior and otherwise isolated or separate

portion of said letter O is securely retained in place in the box structure regardless of the integrity of the pane of glass 17^a on which it is placed. In a similar manner rod 5 21 and clamping nuts 21^a, 21^b, securely attach the interior portion 17^a of the letter O on side 2 to standard 13.

In the letter B there are two isolated, interior portions. The letter B on side 2 has 10 the upper interior portion 16^a attached to standard 14 by end disk 20^a rod 20 and clamping nuts 20^a. The lower interior isolated portion 16^b is attached to standard 14 by end disk 22^a, rod 22 and clamping nuts 15 22^a. Standard 15 similarly furnishes a suitable support to which is attached the interior portions of the letter B, on side 1, not shown.

In such a structure it is important that 20 secure means for supporting the interior and isolated portions of the said trough letters be provided. Because these signs are frequently made of such size that it would be unsafe to depend on attaching said isolated portions of the letters to the glass against which they are applied. Also because of the fragile nature of said glass such a support should be adjustable in order to easily provide for its proper installation 25 30 without subjecting the glass to undue strains. Furthermore, such supports should be so placed that they will not cast undesirable shadows on the parts of the letters to be illuminated. I have accomplished these desirable objects very well in my structure. The entire interior of the box, excepting the mirrors 10, 10, and the glass panes, including the said standards and rods, is preferably painted white. The interior and exterior 35 40 of the trough letters, excepting the glass bottom, is also preferably painted white.

I am aware that it is not new to construct sign letters in the trough form. I am further aware that it is not new to illuminate 45 transparent letters by a light placed behind the same.

What I claim to be new and desire to secure by Letters Patent, is,-

1. In an illuminated sign, the combination 50 of characters each having deep sides of opaque material, having a transparent back, also having isolated portions with deep sides of opaque material, and a back of opaque material; means for supporting said isolated portions independently of said transparent back; and an artificial light placed 55 behind said transparent back.

2. In an illuminated sign, the combination 60 of a box having sides containing openings covered with transparent material, said transparent covering being partly covered by isolated opaque bodies, standards rigidly attached to said box and located within the same, rods having one end attached to 65 said isolated, opaque bodies and the other end attached to said standards, and means for artificially illuminating the interior of said box.

3. In an illuminated sign, the combination 70 of a box having sides provided with openings in the form of the external outlines of characters, having isolated interior outlines, transparent coverings for said openings, opaque bodies shaped like the said isolated, 75 interior outlines of said characters and applied to said transparent coverings, standards rigidly attached to said box being located within the same, rigidly attached to said opaque bodies and being adjustably attached to said standards, artificial lights located within said box and adapted to shine through said transparent coverings, and mirrors located within said box and adapted to reflect light from said artificial illuminants against said transparent coverings. 80 85

Signed at Bellingham, in the county of Whatcom and State of Washington this twentieth day of November A. D. 1909.

ARTHUR L. MERRIN.
